UNITED STATES PATENT OFFICE.

WALTER CRICK, OF HAZELWOOD, ENGLAND.

HEEL FOR BOOTS AND SHOES.

Application filed May 10, 1924. Serial No. 712,258.

To all whom it may concern:

Be it known that I, WALTER CRICK, a subject of the King of Great Britain, residing at Hazelwood, Northampton, in the county of Northampton, England, have invented certain new and useful Improvements in or Relating to Heels for Boots and Shoes, of which the following is a specification, reference being had therein to the accompanying drawing.

This invention relates to heels for boots and shoes and concerns those of the kind having a rubber or like resilient insertion between the tread surface and the seat.

15 The invention comprises an improvement therein, the main feature being that the resilient insertion comprises two parts, for example, layers or sections one of which is secured to the boot or shoe and the other to the heel the latter being attached to the boot or shoe by fastening the two resilient parts together by solution so that they combine to form a resilient cushion located between the tread and the heel seat.

25 It is an important feature of the invention that one at least of the parts of the resilient insertion is secured to the adjacent non-resilient part or parts by non-metallic means for example, solution and stitches.

30 To enable the invention to be readily understood reference will be made to the accompanying drawings wherein some practical forms of the invention are illustrated by way of example.

35 In the drawings:—

Figure 1 shown in perspective, a rubber layer secured to a leather lift ready for attachment to the boot or shoe.

40 Figure 2 is a section of same showing the stitches.

Figure 3 is a perspective view showing the top piece, leather lift and rubber layer secured together.

45 Figure 4 is a section of the parts shown in Figure 3.

Figure 5 is a side view showing the parts shown in Figures 1 and 2 attached to a boot.

50 Figure 6 is a similar view showing the parts illustrated in Figures 3 and 4 secured

to the structure shown in Figure 5 to complete the heel.

Figure 7 is a perspective view, and

Figure 8 is a section showing a resilient layer and a leather lift secured together by 55 nails instead of stitches.

Figure 9 is a perspective view, and

Figure 10 is a section showing the same parts having a top piece nailed to the leather lift. 60

Figure 11 is a side view illustrating a modified method wherein the resilient layer is attached direct to the heel seat without an intermediate leather lift.

Figure 12 shows the heel structure of 65 Figures 9 and 10 secured to the structure of Figure 11 by solutioning together the two resilient layers.

In making and attaching a heel according to the method shown in Figures 1 to 6 of the 70 drawings, a rubber or like layer *a* is secured to a leather lift *b* by means of solution and by stitches *c* which latter pass through the layers.

A further rubber layer *d* is similarly secured by solution and stitches *e* (Figure 6) to a leather lift *f* to which is fastened by nails *f* a leather top-piece *g*. 75

In applying the parts to a boot or shoe to form a heel, the leather lift *b* with the 80 attached rubber *a* is attached either by stitches *h* or by nails or other suitable means to the heel seat *i* as shown in Figure 5 and then to complete the heel the rubber layer *d* is secured by solution to the rubber 85 layer *a* as shown in Figure 6.

Instead of attaching the rubber layer *a* to a leather lift it may be secured direct to the heel seat *i* by solution and stitches *h* as shown in Figure 11 or it may be fastened 90 thereon by nails. The heel may then be completed by application of the structure shown in Figures 3 and 4 in the manner already described.

Instead of securing the rubber layer *d* 95 and leather lift *e* together by solution and stitches these parts may be fastened together by stitches alone, i. e. without solution, or by nails *j* as indicated in Figures 8 and 10 in which case the points of the nails are 100

preferably clinched on the outside of the leather lift as indicated at *h* (Figure 7) to strengthen the connection between the parts. A top piece *g* is attached to the lift *e* as already described and as shown in Figures 9 and 10.

The structure shown in Figures 9 and 10 may be applied by solutioning its rubber layer *d* to the rubber layer *a* of the form shown in Figure 5 or the form shown in Figure 11 in which latter case the heel is completed as shown in Figure 12.

In most cases it is preferable to secure both the rubber layers to their respective parts by solution and stitches thus forming a double non-metallic connection, but when the two part resilient cushion is to be used with a wooden heel or a heel of similar material which does not admit of stitching, the one rubber layer may be fastened by nails and the other stitched. If on the other hand one rubber layer is fastened to the heel seat or equivalent part by nails, as it may be, then the other rubber layer would be secured to its lift by non-metallic means. Thus one at least of the rubber layers is secured by non-metallic means.

The lifts herein referred to and also the top piece may be made of material other than leather if desired. Instead of using single lifts as *b* and *e*, a number may be used in which case they would be fastened together by solution and stitches or by the nails which would bind the whole together.

In the construction herein described the top-piece *g* may be easily removed from the lift *e* and be replaced to repair the heel without interfering with the resilient insertion *a, d*. The nails *f* which secure the top-piece are inserted outside the stitches or nails which secure the layer *d* and lift *e* together.

The resilient layers *a* and *d* are preferably made of crêpe rubber. Instead of using single layers as shown, two or more may be employed, these being solutioned and bound together by the stitches or nails which secure them to the adjacent parts.

It has long been recognized that leather and rubber, and particularly crêpe rubber, cannot be effectively stuck together, that is to say, the union of these two materials when achieved by cement, solution or like adhesive means is not as a rule strong enough to enable these materials to be used in connection with boot and shoe heels without the aid of some additional connecting means. The shocks and strains to which heels are liable in wear tend sooner or later to tear the one material from the other, hence the necessity of some auxiliary means such as stitches, nails, rivets or the like.

Now although a strong connection between rubber and leather cannot be effected by cement or solution alone, rubber and rubber can be stuck together so strongly as to

be practically inseparable, and the present invention takes advantage of this fact to produce the improved heel which has the characteristic feature that while the resilient insertion is effectively attached to the non-resilient layers, such for example as by cement augmented by stitches, the auxiliary means do not extend right through the resilient insertion, thereby leaving the resiliency of the latter unimpaired. Where, as in former proposed constructions, a resilient insertion has been interposed between non-resilient layers, the insertion has been made in one piece and either cement or solution alone has been relied upon to effect the union of the parts, which, for the reasons herein stated, is unsatisfactory in connection with boot and shoe heels, or for the purpose of additional security, auxiliary means such as nails, rivets or stitches have been employed, such means passing from one non-resilient layer to another through the resilient insertion. Obviously, when such means, which are of non-elastic or inextensible character, pass right through the resilient insertion in such a manner as to bind it between the opposing non-resilient layers, the freedom and resiliency of the insertion is restricted and its general effectiveness as a cushion and shock absorber is considerably impaired.

In the present improved heel the resilient insertion although constituting, when its two parts are stuck together, a solid member, is not bound between the opposing non-resilient layers, since it has no auxiliary attaching means passing right through it. Thus the insertion is able to fulfill its intended purpose in an efficient manner while at the same time its connection with the opposing layers of non-resilient material is strong enough to prevent its separation therefrom.

What I claim then is:—

1. A boot or shoe heel comprising a resilient insertion consisting of two resilient layers cemented together and enclosed between non-resilient layers to which said resilient layers are attached.

2. A boot or shoe heel comprising a resilient insertion consisting of two resilient layers each separately secured to a non-resilient layer, the two resilient layers being cemented together.

3. A boot or shoe heel comprising a resilient insertion consisting of two rubber layers cemented together and each secured to an adjacent leather layer.

4. A boot or shoe heel comprising a resilient insertion consisting of two rubber layers stuck together and each secured by cement and stitches to an adjacent leather layer.

5. A boot or shoe heel comprising a resilient insertion consisting of two rubber lay-

ers cemented together, each secured to an adjacent leather layer, and a top piece attached to one of said leather layers.

6. A boot or shoe heel comprising a resilient layer and a non-resilient layer secured together by cement and stitches, said non-resilient layer being attached to the heel

seat of the boot or shoe, and a second resilient layer and non-resilient layer secured together by cement and stitches, said second 10 resilient layer being stuck to the first resilient layer.

In testimony whereof I affix my signature.
WALTER CRICK.
